(57) **CLAIM**

The original design for an electrical connector, as shown and described.

DESCRIPTION

FIG. 1 is a top, front and right side perspective view of an electrical connector showing my new design;

FIG. 2 is a top, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a right side elevational view thereof;

FIG. 8 is a left side elevational view thereof;

FIG. 9 is an enlarged cross-sectional view thereof, taken along line 9—9 in FIG. 3;

FIG. 10 is an enlarged cross-sectional view thereof, taken along line 10—10 in FIG. 3; and,

FIG. 11 is an enlarged cross-sectional view thereof, taken along line 11—11 in FIG. 3.
